Inventor,
Floyd E. Lasure, by
G. C. Kennedy,
Attorney.

UNITED STATES PATENT OFFICE.

FLOYD E. LASURE, OF WAUKESHA, WISCONSIN.

TOBACCO PIPE.

Application filed November 26, 1921. Serial No. 517,964.

To all whom it may concern:

Be it known that I, FLOYD E. LASURE, a citizen of the United States of America, and a resident of Waukesha, Waukesha County, Wisconsin, have invented certain new and useful Improvements in Tobacco Pipes, of which the following is a specification.

This invention relates to improvements in tobacco pipes, and the object of the improvements is to provide an effective scraping device mounted removably within the hollow stem of the pipe and connected to the mouth-piece thereof to be operated by the latter and to be withdrawable therewith.

This object has been accomplished by the means which are hereinafter described and claimed, and which are illustrated in the accompanying drawings, in which Fig. 1 is a medial vertical longitudinal section of a tobacco pipe equipped with my improved scraping and draft-regulating means, and Fig. 2 is a top plan view thereof. Fig. 3 is a detail perspective view of the scraping device, and Fig. 4 is a transverse vertical section taken through the bowl of the pipe adjacent the scraping head or disk of said scraping device.

Similar numerals of reference denote corresponding parts throughout the several views.

The bowl of the tobacco pipe shown is preferably composed of three concentric layers of material of different characters, to insure lightness, non-conductivity of heat, as shown at 1, 2 and 3, and for other purposes, but this feature is not claimed herein as it is disclosed in my co-pending application.

Said bowl has the usual angularly directed hollow stem 5, the longitudinal hollow 6 whereof being of relatively large diameter and being at its upper forward part in communication with the hollow of said bowl by means of a relatively wide elongated slot or passage 4. The numeral 7 denotes the hollow mouth-piece of which the forward end is diminished in steps to respectively fit within the hollow rear part 13 of the scraper 11 in the hollow 6, the next step adjacent to said part 10 being fitted

rockably within the hollow stem 5, and said mouthpiece having a longitudinal bore or hollow 8 leading into said hollow 6. The scraping device shown in said Fig. 3 consists of an elongated part 11 whose rear end is shaped with semi-circular parts 13 terminally slightly separated at 14, thus supplying an elastic split-ring which elastically surrounds and clasps the forward diminished end-part 10 of said mouth-piece 7. The forward part of said device is bent downwardly to provide a disciform scraping-member 12, imperforate, and loosely fitting the hollow 6 transversely near the closed forward end of said hollow but slightly forward of the forward end of the elongated draft-passage 4. The medial elongated part 11 of said scraper is positioned immediately below and in registration with said passage 4 except that it is narrower than the passage whereby relatively narrow draft passages are preserved at each side of said part 11. This, ordinarily, supplies sufficient draft for the ignited contents of the bowl 1, but to provide a wider passage for more draft, said mouth-piece 7 may be rocked slightly to displace the part 11 sufficiently to more widely open said passage 4.

To remove adherent matter from the walls of the hollow 6, the scraper-member 12 may be pushed back and forth through said hollow and be rocked from side to side by proper manipulation of said mouth-piece to which it is attached, the loosened matters being expelled from said hollow when the scraper 12 is fully withdrawn from the stem 5.

Having described my invention, what I claim as new, and desire to secure by Letters Patent, is:

A tobacco pipe, comprising a bowl having a longitudinally hollowed stem, and having an elongated passage in its bottom effecting communication longitudinally with the hollow of said stem, a longitudinally orificed mouth-piece having an end diminished terminally with its diminished part removably and rockably mounted in the hollow of said stem terminally, and a scraper in said hollow consisting of a bar

narrower than the said elongated passage, having one end formed into an elastic split-ring to be engagingly secured removably upon the inserted diminished end of said 5 mouth-piece to be rocked or moved slidably therewith, and having its other end bent angularly, shaped to fit the walls of said

hollow and positioned in said hollow at one end of the said elongated passage unobstructedly.

10

Signed at Waukesha, Wis., this 24th day of October, 1921.

FLOYD E. LASURE.
